The ornamental design for a food package, as shown and described.

DESCRIPTION

FIG. 1 is a top plan view of a food package showing our new design;

FIG. 2 is a front elevational view thereof; the rear elevational view being a mirror image thereof;

FIG. 3 is a right side elevational view thereof;

FIG. 4 is a left side elevational view thereof;

FIG. 5 is a bottom plan view thereof;

FIG. 6 is a top plan view thereof; in unfolded position;

FIG. 7 is a front elevational view of a tray in the package, shown separately for clarity of illustration; the top plan view being as shown in FIG. 6; the rear elevational view being identical to FIG. 7;

FIG. 8 is a right side elevational view of FIG. 7; the left side elevational being identical to FIG. 8; and,

FIG. 9 is a bottom plan view of FIG. 7.
